UNITED STATES PATENT OFFICE.

MICHAEL REEDY, OF MEMPHIS, TENNESSEE.

RAIL-FASTENING MEANS.

1,285,380.

Specification of Letters Patent. Patented Nov. 19, 1918.

Application filed March 4, 1918. Serial No. 220,230.

To all whom it may concern:

Be it known that I, MICHAEL REEDY, a citizen of the United States, residing at Memphis, in the county of Shelby and State 5 of Tennessee, have invented new and useful Improvements in Rail-Fastening Means, of which the following is a specification.

My present invention has to do with the attachment of railway rails to sleepers 10 through the medium of spikes, screw bolts, and the like; and it contemplates the provision of a spike-facing chafing plate in combination and for use in conjunction with a spike and a rail base secured in position 15 by the spike, the said plate being adapted for interposition between the rail-base edge and the shank and head of the spike or bolt, and for embedment in the sleeper to which it is secured, and being designed to hold the 20 underside of the spike head or jaw in spaced relation to the upper side of the rail base so that a claw bar may be readily positioned between the two for withdrawal of the spike or bolt, and being also designed to assist 25 the spike in resisting lateral thrust and better holding the rail to gage as well as prevent the rail base from cutting the throat of the spike or bolt and giving rise to accident.

30 The spike or bolt together with the chafing plate may be used either with or without a tie-plate, in the discretion of the builder, and with the foregoing in mind, the invention will be fully understood from the following description and claim when the same are read in connection with the accompanying drawings, hereby made a part hereof, in which:

Figure 1 is a view, partly in section and 40 partly in elevation, illustrative of my improvement.

Fig. 2 is a similar view, taken at right angles to Fig. 1.

Fig. 3 is a perspective of my novel chafing plate, *per se*.

Similar numerals of reference designate corresponding parts in all the views of the drawings.

The sleeper or tie 1, the rail 2 and the 50 spike or bolt 3 may be and preferably are of the ordinary well-known types, and when deemed expedient the usual tie-plate (not shown) may be interposed between the sleeper or tie and the rail, without affecting 55 my invention.

My novel chafing plate 4 is made of steel or other material suitable to its purpose, and is of approximate right-angle form. It comprises an upper arm 5 and a shank 6 depending from said arm, the shank being beveled or sharpened at its lower end, as indicated by 7, to facilitate driving of the plate into the sleeper or tie to secure the plate in working position, Figs. 1 and 2. I prefer to make the chafing plate of greater 65 width than the spike shank in about the proportion shown in Fig. 2 with a view to enabling the plate to better assist the spike in resisting lateral thrust.

The novel chafing plate 4 is driven into 70 the sleeper or tie so that it is secured in position with its shank resting against the edge of the rail base, and its head or arm 5 resting snug against and over said base. The spike or bolt is then driven home, along- 75 side and close against the shank portion of the plate, when as will be readily observed by reference to Fig. 1, the apex of the plate will rest between the corner of the rail base and the throat of the spike to 80 adequately prevent the base from cutting the throat of the spike, and at the same time, the underside of the jaw or head of the spike will be held away from the rail base so that a space will be afforded between the 85 two, as indicated by 8 in Fig. 1, so that a claw bar or the like may be readily interposed between the rail base and the spike jaw or head for the convenient withdrawal of the spike. It will also be noted that the 90 plate 4 is calculated to enable the spike or bolt to better resist lateral thrust with a view to maintaining the rail and the tie plate, when employed, in place and gage.

Manifestly my novel chafing plate is sim- 95 ple and inexpensive and is adapted to be readily secured in position precedent to the driving of the spike or coincident therewith, if desired, and therefore the employment of the plate does not materially increase the 100 cost of securing the rail to the sleeper or tie. It will be noticed, however, in this connection that the capacity of the chafing plate to be driven home by hammer blows imposed on the head of the spike is calculated to 105 materially cheapen the fastening of the rail when the chafing plate is employed in combination with the sleeper or tie, the rail and the spike.

Having described my invention, what I 110

claim and desire to secure by Letters Patent, is:

As a new article of manufacture, a chafing plate of substantial right-angle form having a shank straight throughout its length and terminating in a sharpened lower end disposed in the same plane as the remainder of the shank whereby it is adapted to be driven into a sleeper or tie and also having an arm extending from the upper

end of the shank and adapted to rest on and overhang the edge portion of a rail base.

In testimony whereof I have hereunto set my hand in presence of two subscribing 15 witnesses.

MICHAEL REEDY.

Witnesses:

JAS. C. ADLER,
JOHN HENCKEL.
